Henry Gross
BY Maurice B. Landau
ATTORNEY

UNITED STATES PATENT OFFICE

HENRY GROSS, OF RIDGEWOOD, NEW YORK, ASSIGNOR TO UNITED FRUIT COMPANY, OF NEW YORK, N. Y., A CORPORATION OF NEW JERSEY

CONVEYER

Application filed May 21, 1928. Serial No. 279,297.

The present invention has for an object to provide an improved conveyer mechanism of the type in which a length of flexible material such as canvas is draped between a plurality of transverse bars to form pockets. Conveyers of this type are used, for example, in conveying bananas up from the hold of a ship.

In operation the pockets of such conveyers tend to reverse as they come to operative position from the lower end of their travel, that is to say the slack of the canvas forming the pocket falls forward over the crossbar and must be pushed back over the bar before use. The present invention provides means for preventing reversal of the pockets and for causing them automatically to come to operative article receiving position.

The nature and objects of the invention will be better understood from a consideration of a particular embodiment thereof for the purposes of which description reference should be had to the accompanying drawing forming a part hereof and in which—

Figure 1 is a perspective view of a section of a conveyer showing the invention applied thereto,

Figure 2 is a detail view in side elevation showing the retaining chain in operative position, and

Figure 3 is a similar view showing the operation of the chain to prevent turning of the pocket on the downward traveling run of the conveyer.

Figure 4 is a detail view of the clamp which is riveted to the canvas carrier.

In the embodiment shown for the purposes of illustrating the principles of the invention, a typical conveyer of the type commonly used for example for conveying bananas up from the hold of a ship is shown as provided with means for preventing reversal of the pockets as said pockets pass around the sprocket wheels at the lower end of the conveyer. As shown, the conveyer comprises a flexible canvas sheet 5 draped between cross-bars 6 carried by spaced side chains 7. The canvas is looped over the cross-bars as at 8 and a strip of felt 9 overlies each loop to

provide padding to avoid unduly bruising the bananas or other article carried against the cross-bars. In operation of conveyers of this type as the cross-bar passes around the sprocket wheels at the lower end of the 55 conveyer the slack canvas forming the pocket falls downwardly and as the pocket comes up along the vertical run of the conveyer, it lies forward of the cross-bar and must be pushed back over the bar to operative position before a bunch of bananas can be placed therein. The present invention avoids the inconvenience by providing means for automatically turning the pockets to operative position, or for preventing them from turning to inoperative position, as the cross-bars 60 pass around the lower sprocket wheels.

The device particularly shown for the purposes of illustration comprises a chain 10 secured to the edge of the canvas 5 in suitable position to prevent rotation of the loop 8 around the cross-bar to a position in which the pocket is in inoperative position. A clamp 11 consisting of a piece of metal folded thereto forms a suitable connection between the canvas and chain. The chains extend around the rod from the back thereof and are secured to the eyes of cotter pins for example on the front side of the shaft or rod in such position that, as the loop of canvas rotates in operation, the chain winds up on said rod and limits the extent of rotation of the loop, that is to say, it prevents a pocket moving around the shaft to the undesirable inoperative position. There are, preferably, two chains for each pocket, one on each side of the sheet, although if the sheet is of relatively heavy canvas it is ordinarily sufficiently rigid to operate if only one chain is applied. The 70 belt tends to give a measure of stiffness to the loop of canvas around the transverse rod, so that the chains operating on the edges of the canvas sheet will operate sufficiently to hold the full width of the canvas in the desired position without making necessary the provision of additional devices operating at the centers of the rods.

The chains or other suitable flexible members so hold the canvas as the conveyer moves 100

around the lower sprocket wheels that the slack canvas forming the pocket falls to operative position.

The foregoing particular description is illustrative merely and is not intended as defining the limits of the invention.

I claim:

1. A conveyer comprising a plurality of spaced cross-bars, a flexible member draped between said cross-bars and longer than the distance therebetween to form article receiving pockets and means for preventing the slack of said member from moving forwardly of the cross-bar as the cross-bar passes from its downward travel to its upward travel.
2. A conveyer of the character described comprising a plurality of spaced cross-bars, a flexible sheet substantially longer than the distances between cross-bars draped over successive cross-bars to form pockets, flexible members secured to said flexible sheet and extending around said cross-bars to limit rotation of said flexible sheet around said cross-bars in one direction.
3. A conveyer comprising a plurality of spaced cross-bars, a flexible member draped between said cross-bars and longer than the distance therebetween to form article receiving pockets and flexible members secured to the slack of the pockets and anchored to the conveyer to limit rotation of the slack of the pockets around the cross-bars.

In testimony whereof, I have signed my name to this specification this ninth day of May, 1928.

HENRY GROSS.
